The ornamental design for a speaker port for a handheld communication device, as shown and described.

CLAIM

FIG. 1 is a perspective view of the speaker port for a handheld communication device of my new design;
FIG. 2 is an elevation view thereof;
FIG. 3 is a top view thereof;
FIG. 4 is a bottom view thereof;
FIG. 5 is a left side view thereof; and,
FIG. 6 is a right side view thereof.
The broken line showings of FIGS. 1-6 are for illustrative purposes only and form no part of the claimed design.

1 Claim, 4 Drawing Sheets
